(57) **CLAIM**

The ornamental design for an antenna detection circuit module as shown and described.

DESCRIPTION

FIG. 1 is a perspective view of an antenna detection circuit module that utilizes Fachkreis Automobil (FAKRA) connectors, showing our new design;

FIG. 2 is a top plan view of the antenna detection circuit module that utilizes FAKRA connectors of FIG. 1;

FIG. 3 is a bottom plan view of the antenna detection circuit module that utilizes FAKRA connectors of FIG. 1;

FIG. 4 is a left-side elevation view of the antenna detection circuit module that utilizes FAKRA connectors of FIG. 1;

FIG. 5 is a right-side elevation view of the antenna detection circuit module that utilizes FAKRA connectors of FIG. 1;

FIG. 6 is a back side elevation view of the antenna detection circuit module that utilizes FAKRA connectors of FIG. 1; and,

FIG. 7 is a front side elevation view of the antenna detection circuit module that utilizes FAKRA connectors of FIG. 1. The broken lines shown in the drawings illustrate portions of the antenna detection circuit module that form no part of the claimed design.
